CLAIM

The ornamental design for a lipstick case, as shown and described.

DESCRIPTION

The file of this patent contains at least one drawing executed in color. Copies of this patent with color drawing(s) will be provided by the Patent and Trademark Office upon request and payment of the necessary fee.

FIG. 1 is a perspective view of a lipstick case showing my new design;

FIG. 2 is a front view thereof, a rear view being identical to the front view;

FIG. 3 is a right side view thereof, left side view being identical to the right side view;

FIG. 4 is a top plan view thereof;

FIG. 5 is a bottom view thereof;

FIG. 6 is a front view of the lipstick case, showing the main body separately to show aspects of the design that are not visible when combined; and,

FIG. 7 is a right side view thereof.

The logo shown in FIGS. 1 and 4 of the claimed design is a registered trademark of Shiseido Company, Ltd.
